[57] CLAIM

The ornamental design for a multi-component projectile-propelling toy weapon, as shown and described.

DESCRIPTION

FIG. 1 is a side elevational view of a multi-component projectile-propelling toy weapon showing our new design, the opposite side being a mirror image thereof;
FIG. 2 is a top plan view thereof;
FIG. 3 is a bottom plan view thereof;
FIG. 4 is a front elevational view thereof;
FIG. 5 is a back elevational view thereof; and,
FIG. 6 is an isometric view thereof.
